United States Patent Office

Des. 210,485
Patented Mar. 12, 1968

210,485

POLE

Maurice J. Rhude, Marinette, Wis., assignor to Koppers
Company, Inc., a corporation of Delaware

Filed Aug. 1, 1967, Ser. No. 8,078

Term of patent 14 years

(Cl. D48—31)

FIG. 1 is a perspective view of a pole showing my new design, the side opposite that shown being a mirror image thereof; and

FIG. 2 is a perspective view of a modified form of a pole showing my new design, the side opposite that shown being a mirror image thereof.

The broken line showing of luminaire heads in the figures is for illustrative purposes only.

I claim:

The ornamental design for a pole, as shown and described.
